UNITED STATES PATENT OFFICE.

WALTER P. GRATH, OF ST. LOUIS, MISSOURI.

BRICK-MACHINE.

SPECIFICATION forming part of Letters Patent No. 660,187, dated October 23, 1900.

Application filed November 1, 1899. Serial No. 735,486. (No model.)

To all whom it may concern:

Be it known that I, WALTER P. GRATH, a citizen of the United States, and a resident of the city of St. Louis, in the State of Missouri, have invented a new and useful Improvement in Brick-Machines, of which the following is a specification.

My invention relates to brick-machines, and has for its principal object to produce a hand-power machine for pressing clay and to improve the details of construction.

It consists in the parts and combinations of parts hereinafter described and claimed.

In the accompanying drawings, which form part of this specification, and wherein like symbols refer to like parts wherever they occur, Figure 1 is a side elevation of my machine. Fig. 2 is an end elevation thereof. Fig. 3 is a horizontal section on the lines 3 3 20 of Figs. 1 and 2. Fig. 4 is a vertical section on the line 4 4 of Fig. 2, and Fig. 5 is a central vertical section on the line 5 5 of Fig. 2.

The framework 1 of my machine has a mold 2 in its upper portion, and the mold is open 25 and provided with a plunger at its top and at its bottom. The lower plunger 3 or bottom of the mold is vertically movable in said mold, and the shank of said plunger has teeth formed thereon to constitute one or more 30 racks 4. A horizontal shaft or axle 5, journaled in the framework, has one or more pinions 6 fixed thereon to mesh with said rack or racks and a hand-lever 7 for turning said shaft. As the weight of the lower plunger 3 tends to turn said shaft, a stop is arranged 35 on said framework in the path of said lever, so as to limit the downward movement of the lower plunger. This stop consists of a set-screw 8, working vertically in a threaded lug 40 or projection 9 on the frame, whereby the operative end of said screw is vertically adjustable. In order that the initial pressure of the upper plunger 10 may communicate an initial downward movement to the lower 45 plunger 3 for the purpose of reducing the granulation of the clay in the interior of the brick, a long flat spring 11, bowed downwardly, is fixed to the lower edge of the hand-lever, so as to rest against the set-screw. This 50 spring is strong enough to overcome the downward pressure due to the weight of the lower

plunger, but yields to the initial pressure of the upper plunger on the clay in the mold.

In order to properly guide the lower plunger and reduce the friction thereon, an anti-friction axle or roller 12 is mounted in the framework on the opposite side of the plunger to the side on which the rack and pinion are located. The lower end of the shank of the lower plunger is slotted or bifurcated to 60 straddle and guide pins or projections 13 on the end of a toggle-link 14. In the normal or retracted position of the lower plunger the end of the toggle-link is not in contact with the lower plunger, but far enough therefrom 65 to permit the initial downward movement thereof hereinbefore mentioned. The toggle-link 14 is pivotally connected at its lower end to a draw-bar 15, which is guided to move horizontally, as by having its sides or lateral 70 projections therefrom sliding in horizontal slots 32 in the frame. It is preferable to mount antifriction - rollers on said projections, as shown at 33. Another toggle-link 16 is pivotally connected at its upper end to 75 said draw-bar and carries a laterally-projecting pin or bar 17, which is guided to move vertically. This last-mentioned pin projects through the frame and has pivoted thereto at each end a vertical rod or bar 18, and these 80 two vertical rods carry a horizontal cross-bar 19, from which is suspended the upper plunger 10, which fits into the mold from above and constitutes the top thereof.

Power is applied to the press by means of 85 a lever 20, journaled in the framework and adapted to bear against the draw-bar endwise. For this purpose the end of the draw-bar is enlarged on its upper side and has an elongated slot 21 formed therein and a vertical offset 22 at its outer end. The axle or fulcrum 23 of the lever extends through the horizontal slot, and a bearing-pin 24, carried by said lever, fits in the vertical slot or offset. This construction constitutes a cam, and 90 when the lever is turned the bearing-pin moves the draw-bar forward or backward, while the horizontal slot permits the draw-bar to slide on the fulcrum-pin without changing its horizontal position. A great leverage 95 may thus be used for moving the draw-bar, the head of which operates the toggle-links

14 16, which in turn actuate the respective plungers.

In order to facilitate the filling of the mold, the upper cross-bar 19 is mounted pivotally 5 in the side bars or the upper plunger is mounted pivotally on the cross-bar to enable said plunger to be swung up beyond the vertical position. A lug or stop 25 is provided on the pivotal member, and limiting-stops 26 10 are provided on the side bars 18 or on the framework for holding the plunger in its upturned position and for centering it above the mold in its downturned position, respectively. In order to permit of this upturning 15 of the plunger, the feed-spout 27 is inclined so that the plunger will clear it. The feed-spout terminates in a charger or measuring-box 28, corresponding in size with the mold and arranged to slide horizontally on the up- 20 per table or platform to empty its contents into the mold. This charger is provided with a rearwardly-extending plate 29, adapted to close the spout when the charger is drawn above the mold. In order to prevent the 25 weight of the upper plunger from causing it to drop, its cross-bar is provided with a loose collar 30, which has a radial arm 31 projecting therefrom in position to slide along the top edge of the framework. This collar, with 30 its radial arm, thus constitutes a gravity-pawl, and when the plunger is raised the radial arm is on the dead-center and prevents the accidental dropping of the upper plunger. When the machine is to be operated, 35 this gravity-pawl is pulled aside and its end edge slides on the top edge of the framework.

The operation of the machine is as follows: The upper plunger is swung up against its back-stop to permit the charger to be slid 40 horizontally on the table to drop its contents into the mold. Then the upper plunger is swung down and centered above the mold. Then power is applied to the main lever and the draw-bar is actuated thereby. As the 45 draw-bar is guided horizontally it moves both the upper and the lower toggle-links; but on account of the space between the end of the upper toggle-link and the end of the slot in the shank of the lower plunger the upper 50 toggle-link produces no effect until its end comes into contact with said end of the slot. The upper plunger, however, begins to move downwardly with the first motion of the draw-bar, because its cross-bar is fitted on the side 55 bars which are directly connected to the lower toggle-link. The result is that there is an initial downward pressure of the upper plunger before the upper toggle-link is in position to operate the lower plunger upwardly, 60 and this initial pressure, acting on the clay, forces the lower plunger downwardly, the flat spring of the positioning device yielding to permit this action. The continued movement of the draw-bar brings the upper toggle-link into operative relation with the lower plunger, and pressure is exerted on the clay both from above and from below. After the 65

brick is thus formed the main lever is returned to its former position, whereby the upper plunger is raised and the lower plunger is free to move down. Then the upper plunger is swung up to make room for ejecting the brick from the mold. Then the pinion is turned by means of the hand-lever on its axle, and acting on the rack on the shank 70 of the lower plunger it raises said plunger, and thereby ejects the brick. The hand-lever is then lowered to rest against its back-stop and the machine is in condition to repeat the above-described operation. 75 80

What I claim is—

1. A brick-machine comprising a framework, a mold having movable plungers constituting the top and the bottom thereof, a horizontally-guided draw-bar and vertically-guided links pivotally connected to said draw-bar and constituting a toggle for operating said plungers, one of said links being operatively connected to one plunger and the other being connected to side bars connected to the other plunger, and a lever fulcrumed in said framework and arranged to actuate said draw-bar, substantially as described. 85 90

2. A brick-machine comprising a framework, a mold having movable plungers constituting the top and the bottom thereof, a horizontally-guided draw-bar and vertically-guided links and connecting-bars constituting a toggle for operating said plungers, and a lever fulcrumed in said framework, said draw-bar having a cam formed near its outer end and said lever having a piece to coöperate with said cam, substantially as described. 95 100

3. A press comprising a mold whose top consists of a vertically-movable plunger, said plunger being pivotally suspended from a transverse cross-head and adapted to be swung up past the vertical plane, substantially as and for the purpose described. 105

4. A press comprising a mold whose top consists of a vertically-movable plunger pivotally mounted from a cross-piece and adapted to be swung up past the vertical plane, and a stop arranged to hold said plunger in elevated position when swung up past the vertical plane, substantially as described. 110 115

5. A press comprising a mold whose top consists of a vertically-movable plunger, and a gravity-pawl mounted to move with said plunger and arranged to slide along the top of the framework, substantially as described. 120

6. A press comprising a mold whose bottom consists of a vertically-movable plunger, means for exerting pressure thereon said means being normally out of operative relation to said plunger to permit said plunger to move independently thereof in either direction, and an independently-acting ejecting device for elevating said plunger, substantially as described. 125 130

7. A press comprising a mold whose bottom consists of a vertically-movable plunger, a toggle for exerting pressure on said plunger, a rack formed on said plunger and a pinion

engaging therewith, and means for holding said plunger out of contact with the toggle device when said toggle device is retracted, substantially as described.

5 8. A press comprising a mold whose top and bottom each consists of a vertically-movable plunger, means normally out of operative relation to the lower plunger for exerting pressure thereon and an independently-acting

10 ejecting device consisting of an axle, a hand-lever and a pinion thereon, and a rack on said lower plunger and engaging said pinion, and an automatically-yielding stop in the path of said hand-lever, substantially as described.

9. A press comprising a mold having movable plungers constituting the top and the bottom thereof, a toggle for actuating the same, side bars connecting the upper plunger with the lower toggle-link, and a yielding device for supporting the lower plunger out of operative relation to the upper toggle-link when said upper link is retracted, substantially as described. 15 20
